UNITED STATES PATENT OFFICE.

WILHELM HAUG, OF AUGSBURG, GERMANY.

DESIGN FOR A GAME-BOARD.

SPECIFICATION forming part of Design No. 29,688, dated November 15, 1898.

Application filed September 17, 1898. Serial No. 691,243. Term of patent 34 years.

To all whom it may concern:

Be it known that I, WILHELM HAUG, a citizen of the Empire of Germany, residing at Augsburg, Bavaria, Germany, have invented 5 a new and original Design for Game-Boards, of which the following is a description, reference being had to the accompanying drawings, forming a part thereof.

In the drawings, Figure 1 is a plan view of 10 a game-board, showing my new design; and Fig. 2 a transverse sectional view of the same.

As shown in the drawings, the leading or 15 material feature of my design consists in a checkered quadrilateral, there being sixteen squares or fields in each row and sixteen rows on the board, the alternate squares or fields being suitably distinguished from the intermediate ones by contrasting colors, as by making the former black, while the latter are white, 20 or by using a dark color and a light one.

A court is formed at the center of two opposite sides of the board by means of a distinguishing-line B, which follows the dividing-lines of the squares in such a manner as 25 to form a pyramid of squares or fields in each court, the base of each pyramid being those

squares or fields of the outer row which are inclosed in the court, the next inner row having a less number of fields inclosed in said court, the third row still less, and the fourth 30 row having only a few fields inclosed within said court and forming the apex of the pyramid. In addition a block is formed by a border or distinguishing line C, inclosing some of the fields lying within the court, this block 35 containing a heavy circle D, substantially concentric with the said block. Those squares in the outer row having diagonals in a line with the diagonals of the said block are each provided with a centrally-arranged spot, sub- 40 stantially circular, as shown at E.

Having thus fully described my invention, what I claim as new, and desire to secure by Letters Patent, is—

The design for a game-board as herein 45 shown and described.

In testimony whereof I affix my signature in the presence of two witnesses.

WILHELM HAUG.
